(57) **CLAIM**

The ornamental design for a display screen or portion thereof with animated graphical user interface, as shown and described.

DESCRIPTION

FIG. 1 is a front view of a first image of a first embodiment in a sequence for a display screen or portion thereof with an animated graphical user interface showing our new design; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; FIG. 7 is a front view of a first image of a second embodiment in a sequence for a display screen or portion thereof with an animated graphical user interface showing our new design;

FIG. 8 is a front view of a second image thereof; FIG. 9 is a front view of a third image thereof; FIG. 10 is a front view of a fourth image thereof; FIG. 11 is a front view of a fifth image thereof; FIG. 12 is a front view of a sixth image thereof; FIG. 13 is a front view of a seventh image thereof; FIG. 14 is a front view of an eighth image thereof; FIG. 15 is a front view of a first image of a third embodiment in a sequence for a display screen or portion thereof with an animated graphical user interface showing our new design; FIG. 16 is a front view of a second image thereof; FIG. 17 is a front view of a third image thereof; FIG. 18 is a front view of a fourth image thereof; and, FIG. 19 is a front view of a fifth image thereof.

The dash-dot broken lines in the drawings illustrate the display screen or portion thereof and form no part of the claimed design. The remaining broken lines in the drawings illustrate portions of the graphical user interface that form no part of the claimed design.

In the first embodiment, the appearance of the animated graphical user interface sequentially transitions between the images shown in FIGS. 1-6. In the second embodiment, the
